[57] CLAIM

The ornamental design for a terminal for detecting, signaling, and evaluating various hazard criteria, such as fire or intrusion conditions, as shown and described.

DESCRIPTION

FIG. 1 is a perspective view of a terminal for detecting, signaling and evaluating various hazard criteria, such as fire or intrusion conditions showing our new design; FIG. 2 is an enlarged front elevational view of the panel thereof;

FIG. 3 is a perspective view of a second embodiment thereof; and

FIG. 4 is an enlarged front elevational view of the panel thereof.

The bottom, rear and undisclosed sides of both embodiments are plain, flat plates.

FIG. 1

FIG. 2

FIG. 3

FIG. 4
